United States Patent Office

Des. 185,733
Patented July 28, 1959

185,733

SAND PLANE

Bernard J. Cagan, Los Angeles, and Alfred E. Ziroli, Manhattan Beach, Calif., assignors to Eldon Manufacturing Company, Los Angeles, Calif., a corporation of California

Application February 18, 1958, Serial No. 49,686

Term of patent 14 years

(Cl. D34—15)

Figure 1 is a top plan view of a sand plane showing our new design;

Figure 2 is a side elevation thereof; and
Figure 3 is a bottom plan view thereof.

We claim:

The ornamental design for a sand plane, as shown.
